UNITED STATES PATENT OFFICE.

EDWARD H. CLARKSON, OF NEWBURYPORT, MASSACHUSETTS.

DESIGN FOR A BROOCH-BAR.

SPECIFICATION forming part of Design No. 36,610, dated November 3, 1903.

Application filed October 2, 1903. Serial No. 175,529. Term of patent 7 years.

To all whom it may concern:

Be it known that I, EDWARD H. CLARKSON, a citizen of the United States, residing at Newburyport, in the county of Essex and State of Massachusetts, have invented a new and original ornamental Design for Brooch-Bars, illustrated in the accompanying drawings, in which—

Figure 1 is a front view of the brooch-bar, and Fig. 2 is an edge view thereof.

What I claim as my invention is—
The ornamental design for a brooch-bar, as shown.

EDWARD H. CLARKSON.
